JACOB A. L. MÖLLER, OF NEW YORK, N. Y., ASSIGNOR TO ROSE & FRANK COMPANY, A CORPORATION OF NEW YORK.

TYPE-WRITING RIBBON.

1,320,634.

Specification of Letters Patent.

Patented Nov. 4, 1919.

Application filed May 14, 1919. Serial No. 297,089.

To all whom it may concern:

Be it known that I, JACOB A. L. MÖLLER, a citizen of the United States, residing at New York city, N. Y., have invented certain 5 new and useful Improvements in Type-Writing Ribbons, of which the following is a clear, full, and exact description.

My invention relates to an inking ribbon for typewriting machines or the like, and a 10 process of treating the same, and my object is to produce a better ribbon, one which will lie flat in use.

In the drawings, which are merely illustrative,

15 Figure 1 is a portion of a ribbon (threads exaggerated), and

Fig. 2 is a schematic representation of a gum-applying machine which may be used.

Heretofore typewriter ribbons have been 20 made of a woven cotton fabric, and woven silk has been proposed, but as made they are open to various objections, and no adequate diagnosis seems to have been made of the underlying causes of some of the defects 25 inherent in them, or of the remedies for such defects.

A typewriter ribbon, to be entirely satisfactory, must lie flat on the machine, not only when first applied but when subjected 30 to the pounding of the type and atmospheric changes. If it wrinkles, due to unequal contraction or other causes, it gives trouble. It must be very thin and flexible, and should not be unduly affected by atmospheric moisture.

35 A cotton fabric woven in a narrow strip has been used, and silk of some indefinite kind and characteristics has been proposed, but when woven into a narrow strip each 40 is open to various objections. The cross threads then consist of one long thread woven back and forth. This consequently is doubled or looped at the edges and this results in various objections. The looped 45 end when it is sharply doubled back is likely to break and fray, especially when run through the guides, and give passage to atmospheric moisture in the threads as well as the pores of the fibers themselves. Most 50 ribbons are run in a substantially vertical plane, and one edge rests on the guides. It therefore soon wears and frays. Also, the frayed ends soil the paper, catch on the guides, and are otherwise objectionable.

55 Cotton is very hygroscopic. If a narrow

ribbon having cross threads with the ends not looped but raw (cut off) and untreated, were used, the defects of the doubled ends would in part be avoided, but other even more objectionable results would occur. 60 Atmospheric moisture passes, as in the above illustration of a frayed looped thread, resulting in various troubles such as decay, contraction of one or both edges, and an uneven or possibly wrinkled ribbon which 65 will not lie flat and which brings still more friction thereon in the guides, and the ribbon soon goes to pieces at its edge. A typewriter ribbon usually comes in a closely fitting tin box, the ribbon itself being further 70 protected by a wrapping of tinfoil. These precautions to a great extent protect the ribbon until it is put on the machine, but once in use it is exposed to the atmospheric moisture, which greatly varies in quantity, 75 and consequently the ribbon usually has a short life. I have discovered that a ribbon principally composed of fine animal fiber, preferably silk, when properly treated as herein described, results in one which has 80 several advantages, and avoids objections inherent in ribbons of the prior art. By "silk" I do not mean necessarily entirely composed of silk.

I prefer to use a fine closely woven silk 85 from 3 to 5 one thousandths of an inch thick, in a strip substantially the width of the completed ribbon, and with the cross threads "raw" (cut) at each end. A portion of such a strip is shown in Fig. 1 at A. The 90 strip may be cut from a wide sheet. I may smooth, calender, or "iron" the fabric, but this is not always necessary. I also prefer that the threads be loosely twisted, because the ribbon will wear longer than when they 95 are hard or tightly twisted. It is also more absorbent of ink.

Then I impregnate the raw ends of the threads with a fluid or liquid gum which is flexible and substantially non-hygroscopic 100 when dried. This "lays" the ends and binds them continuously to each other, as shown at E, F, in Fig. 1, and, what is important, prevents passage of moisture in the ends of the threads or the pores of the fibers of 105 which the threads may be composed.

I use the word "gum" in an illustrative, and not a specific sense. I may, for example, use shellac, a resin varnish, rubber solution, or oxidized linseed oil, preferably adding 110

thereto a small quantity of glycerin or its equivalent to make the resultant "gum" mixture more flexible when dried. The fluid gum may be applied by passing the strip between pressure rollers C, D, as shown in Fig. 2, if desired, the gum being fed to the rollers or by a rotary knife suitably gummed. The strip is then dried.

Raw silk is very hygroscopic. In its natural or untreated state it has considerable ceresin in or on it. I prefer to remove this, or a considerable amount of it, as I find the ribbon resulting has a better surface, takes ink more readily and in greater quantity, the threads slip on each other, and has other advantages. Also, the gum seems to "set" or take hold of the fibers better. The ceresin may be removed, preferably before weaving, by boiling the silk in a soft-water (non-alkali) soap solution.

The ribbon made as above is perfectly flat, is substantially non-hygroscopic at its edges, takes ink readily, and is not so subject to contraction or other defects due to moisture. Its edges when properly treated are firm and smooth, and will not so readily wear out, but yet are almost, if not quite, as flexible as the silk alone. It has other advantages.

I am aware that my invention may be embodied in a variety of forms other than the examples above given, and the claims hereto appended are not intended to be limited to all the details heretofore described.

35 What I claim is:

1. A ribbon of the character described, comprising a strip of thin fabric made of

fine animal fiber, each cross-thread terminating in a raw end at each edge of the strip, and a continuous flexible dried gum impregnated in said raw ends along each edge, thereby binding each raw end to the others and closing the ends of the threads against passage of moisture.

2. A ribbon of the character described, comprising a strip of thin silk, each cross-thread terminating in a raw end at each edge of the strip, and a continuous flexible dried gum impregnated in said raw ends along each edge, thereby binding each raw end to the others and closing the ends of the threads against passage of moisture.

3. A ribbon of the character described, comprising a strip of thin silk from which the ceresin has been at least partially removed, each cross-thread terminating in a raw end at each edge of the strip, and a continuous flexible dried gum impregnated in said raw ends along each edge, thereby binding each raw end to the others and closing the ends of the threads against passage of moisture.

4. A ribbon of the character described, comprising a strip of thin fabric made of animal fiber loosely twisted, each cross-thread terminating in a raw end at each edge of the strip, and a continuous flexible dried gum impregnated in said raw ends along each edge, thereby binding each raw end to the others and closing the ends of the threads against passage of moisture.

Signed at New York city, N. Y., this 8th day of May, 1919.

JACOB A. L. MÖLLER.
